TOOTHBRUSH HOLDER

Filed March 4, 1926

INVENTOR
Anton G. Sulak.
BY
James C. Spill
ATTORNEY

UNITED STATES PATENT OFFICE.

ANTON G. SULAK, OF SEATTLE, WASHINGTON.

TOOTHBRUSH-HOLDER.

Application filed March 4, 1926. Serial No. 92,127.

This invention relates to improvements in ventilated toothbrush-holders, having more particular reference to improvements in the toothbrush-receptacle and holder disclosed and claimed in my United States Letters Patent, No. 1,375,865; issued April 26, 1921, and the primary aim of the present invention is the provision of a ventilated toothbrush-holder readily engageable within and detachable from a resilient wall bracket and wherein the functional end of a tooth brush is readily insertible and restrainingly engaged for support thereby.

Contemplated by this invention is the provision of a ventilated toothbrush-holder and correlated resilient wall-bracket therefor embodying improvements directed particularly to the novel method and means of detachably engaging and supporting the holder upon bracket; in means for preventing axial dislodgment of the holder upon or from the bracket; and in means for ventilating the holder, all of which are important objects of my invention and are to be correlated in the broad aim of enhancing the efficiency of the device for general use.

The above and additional objects which will hereinafter be more specifically treated, are attained by such means as are shown in the accompanying drawing, described in the following specification and then more clearly pointed out in the claim, which is appended hereto and forms part of this application.

With reference to the drawings, wherein is illustrated the preferred embodiment of the invention, and throughout the several views of which like characters of reference designate similar parts:

Figure 1 a front elevation of the detachable toothbrush-holder and correlated wall-bracket thereof comprehended by my present invention illustrating a toothbrush supported therein;

Fig. 2 is a vertical medial transverse section of the same;

Fig. 3 is a vertical longitudinal section thereof taken through 3-3 of Fig. 2;

Fig. 4 is a horizontal section taken through 4-4 of Fig. 2;

Fig. 5 is a vertical transverse section taken through 5-5 of Fig. 3;

Fig. 6 is a side elevation of the toothbrush-holder removed from the correlated wall-bracket thereof; and

Fig. 7 is a vertical transverse section taken through 7-7 of Fig. 4.

The numeral 8 designates a wall-bracket fixedly secured to a wall 9 by a screw 10 with a vertically disposed cylindrical toothbrush-holder 11 restrainingly or releasably engaged thereon having a toothbrush 12 similarly engaged and supported therein.

While the wall-bracket 8 may be otherwise formed, the same is preferably fabricated or stamped as an integral structure from sheet metal, or other suitable material, and comprises a rear or wall plate 13 having resilient members 14, of substantially reduced width, flexed at and extending forwardly and perpendicularly from the side edges thereof, said members being symmetrically flexed in convergent relation, as at 15, and similarly flexed in divergent relation, as at 16, and having the outer resilient terminals 17 thereof shaped in such a manner to serve and function conjointly as a substantially semi-circular resilient seat, wherein the cylindrical toothbrush-holder 11 is restrainingly or releasably engaged and supported.

The cylindrical toothbrush-holder 11 may be fabricated from any suitable transparent material, but, in the present instance the same is preferably made of glass with an exteriorly grooved constricted neck portion 18 formed upon the lower end thereof having an axially disposed opening or mouth 19 extending therethrough, whereby the functional or bristle end 20 of the toothbrush 12 is readily inserted within and removed from the correlated holder 11 thereof. The functional end 20 of the toothbrush 12 is restrainingly and releasably engaged or supported within the holder 11 by the lower bristles of the same normally abutting or resting upon an annular shoulder 21 formed within said holder 11 by the constricted neck portion 18 thereof. The holder 11 is provided at the upper end with an enclosing concavo-convex upper wall 22 and adjacent said upper end is also provided with an elongated rectangular ventilating opening 23 formed in the cylindrical walls thereof, which in conjunction with the opening 19 permits free and constant circulation of air through the holder 11, to thereby preserve the toothbrush 12 in a sanitary condition and prevent the same from becoming moldy or sour.

As hereinbefore stated the cylindrical toothbrush-holder 11 is restrainingly or releasably engaged within the substantially semi-circular resilient seat formed by the 5 complementary resilient terminals 17 and is maintained and retained against axial dislodgement therefrom or movement therein by peripheral ribs or ridges 24 formed in spaced parallel relation upon the exterior 10 walls of said holder, substantially midway the length thereof, which normally abut the upper and lower edges of said terminals 17, when the holder 11 is interposed therebetween, as shown more clearly in Fig. 5. 15 Manifestly, therefore, while the holder 11 may be rapidly and readily removed from the correlated wall-bracket 8 thereof for cleaning, or to be utilized as a protector for the toothbrush when travelling and may 20 be similarly replaced thereon upon completion of same, the peripheral ribs 24 will prevent upward axial movement of said holder upon said bracket during the insertion of the functional end of the toothbrush 12 within the holder and similarly will prevent 25 downward axial movement of the holder when the toothbrush is withdrawn therefrom.

It will be obvious and apparent from the 30 foregoing that the device of the invention is extremely simple, inexpensive and durable in construction, sanitary in use and permits of the rapid and ready drying of the correlated toothbrush thereof after use, to there- 35 by maintain and preserve the same in proper condition.

While I have herein shown and described my invention with sufficient detail to enable those skilled in the art to understand the mode of construction and the principles involved it is to be understood that there is no intentional limitation herein to the specific form and precise details of construction of the invention herein shown and described except as expressly defined by the appended 40 claim, and that various modifications of said construction may be resorted to without departing from the invention, or the benefits derivable therefrom. I also desire to have it understood that certain features of the invention herein disclosed may be employed in other combinations than those herein shown.

Having thus fully described my invention, what I claim as new and desire to secure by 55 Letters Patent is:—

A ventilated toothbrush holder comprising a cylindrical receptacle capable of being detachably connected to a suitable support, said receptacle having an interiorly and angularly shouldered open end and an elongated rectangular ventilating opening in its cylindrical walls adjacent its opposite end, a concavo-convex wall closing said opposite end, and a series of relatively short support 60 engaging ribs circumferentially disposed in spaced parallel relation upon diametrically opposite sides of the periphery of said receptacle substantially midways its length.

In testimony whereof I affix my signature.

ANTON G. SULAK.
